UNITED STATES PATENT OFFICE.

JOHN F. HORN, OF CHICAGO, ILLINOIS.

AUXILIARY SUPPORT FOR PRINTERS' CHASES AND FORMS.

No. 857,807.

Specification of Letters Patent.

Patented June 25, 1907.

Application filed October 5, 1906. Serial No. 337,657.

To all whom it may concern.

Be it known that I, JOHN F. HORN, a citizen of the United States, residing at Chicago, in the county of Cook and State of Illinois, have invented certain new and useful Improvements in Auxiliary Supports for Printers' Chases and Forms, of which the following is a description, reference being had to the accompanying drawings, forming a part of this specification, in which corresponding letters of reference in the different figures indicate like parts.

The object of my invention is to so construct a detachable auxiliary reinforcement and support for printers' chases and forms, that it may be readily applied thereto and may serve not only to reinforce the chase to prevent yielding when locking the form, but may serve to support the body of the form and prevent the same from sagging and falling out while being removed from one place to another,—all of which is hereinafter more particularly described and definitely pointed out in the claims.

25 In the drawings, Figure 1, is a plan view of a printer's chase as it would appear with a form locked therein and showing my improved auxiliary support applied thereto, and Fig. 2, is an enlarged sectional view 30 thereof taken upon the line 2, Fig. 1, viewed in the direction of the arrow there shown.

Referring to the drawings, *a* represents an ordinary printer's chase having a "form" of type *b* locked therein in the usual way by means of wedges *c*. It is well known that the locking wedges tend to spread the bars of the chase, thereby permitting the type to fall out when the form is lifted. Where practicable, this may be overcome by means of 40 the usual cross-bars which are dovetailed at the ends and adapted to fit into corresponding notches in the chase; but even this cannot always be resorted to and when it is, it does not serve to directly support the type 45 in the middle of the form. In place therefore of the single dovetailed bar, I provide a telescoping adjustable bar consisting of two elements, viz, a hollow tube *d* having a block or catch *e* rigidly attached to one end thereof,

50 while within the opposite end of said tube is loosely fitted a rod *f*. A cap *g* is, by preference, screwed upon the end of the tube and bored to receive the rod, while a set-screw *h* is tapped through said cap and tube to engage 55 the rod *f*. A block or catch *i* is rigidly attached to the opposite end of said rod.

Loosely mounted upon the tube *d* is a cross bar or fitting *j*, which is arranged at right angles to said tube and is provided with slots *k* therein for the reception of screws *l l*. A 60 like cross-bar or fitting *m* is also mounted upon the rod *f*, which fitting is also provided with slots for the reception of like screws. Set screws *n, o*, are provided for temporarily securing said fittings in any predetermined 65 position. Said fittings are caused to project downwardly from their supports sufficiently to enable the screws in the fittings to be screwed into such wooden bars or blocks *p* of "furniture" as it may be found desirable 70 to employ in making up the form; and the object of having said fittings adjustable is to enable them to be moved to correspond to the relative positions of the furniture.

In using my improved device, the blocks 75 *e, i*, are placed in the positions shown against the outer edges of the chase and the set-screw *h* tightened. The form is then locked in the usual way when the fittings *k, m*, are moved laterally to stand over such pieces of 80 furniture as may be found most convenient, according to the "make-up" of the form. The screws in the slots of the fittings are then screwed into the corresponding pieces of furniture, when the form may be lifted to 85 the imposing stone or elsewhere without danger of the type falling out. When so removed to any position where the type may be supported from beneath, the auxiliary support may be removed. 90

For larger forms a greater number of fittings may be employed, but ordinarily the number shown will be found sufficient.

I do not wish to be confined to the means shown for locking the telescoping elements. 95 For example, in place of the set-screw, a pin may be employed and bores may be formed in the rod *f* to receive it; or an eccentric clamp may be substituted.

Having thus described my invention, I 100 claim:

1. A combined reinforcement and support for printer's chases and type forms in which is combined telescoping elements, each having a block upon its outer end to engage the 105 edge of the chase, means for locking said telescoping elements together, and means upon said elements for detachably connecting the same with the form, whereby lateral reinforcement may be given to the chase and 110 vertical support to the form.

2. A device of the class described, in which

is combined two telescoping elements, each having a block or projection upon its outer end for engaging the edge of the chase, means for adjustably locking said elements, 5 and adjustable means upon said elements for connecting the same with the form.

3. A device of the class described in which is combined a tube, a rod arranged to telescope therewith, said tube and rod respectively having a block or catch upon the outer end arranged at an angle thereto for engaging the outer edge of the chase, means for locking said tube and rod against longitudinal movement, adjustable cross-bars upon 15 said rod and tube and means for detachably connecting the same with the "furniture" of the form.

4. In a device of the class described, the combination of a tube and rod arranged to telescope with each other, each having a 20 catch upon its outer end arranged at right angles thereto, a set-screw for adjustably locking said rod and tube to each other, and transverse fittings loosely mounted upon said rod and tube, said fittings having slots there- 25 in for the reception of means for detachably engaging the "furniture" of the form.

In testimony whereof, I have signed this specification in the presence of two subscribing witnesses, this 2nd day of October 1906. 30

JOHN F. HORN.
